UNITED STATES PATENT OFFICE.

ADOLPH H. BAUER, OF NEW YORK, N. Y.

CARD SYSTEM.

1,142,007.

Specification of Letters Patent. Patented June 8, 1915.

Application filed July 5, 1913. Serial No. 777,445.

To all whom it may concern:

Be it known that I, ADOLPH H. BAUER, a citizen of the United States, and a resident of the borough of Manhattan, city, 5 county, and State of New York, have invented certain new and useful Improvements in Card Systems, of which the following is a specification.

This invention relates to card systems and 10 has for its primary object the devising of means whereby cards are arranged in sequence in suitable manner to expose a portion of each card at all times, which portion may contain an index or other desired 15 designation, and whereby the cards may be shifted to expose the body portion of any card to adapt it to be read, written upon or otherwise used without disarranging the other cards and whereby one or more cards 20 may be withdrawn from the set or inserted at any place in the set without interfering with the order and arrangement of the other cards.

The various other objects of the invention 25 will be more fully set forth in the following description of one form of a device embodying the invention which consists in the new and novel features of construction and combination of parts hereinafter set forth 30 and claimed.

In the preferred embodiment of my invention the cards are pivotally mounted from one corner in detachable engagement upon a common pivot in suitably spaced relation to permit the upper portion of each 35 card to be exposed and stops are provided upon each card to prevent the adjacent card below from encroaching upon the space but permitting the cards to be swung about the 40 common center to expose any card.

Referring to the drawings forming part of this application, Figure 1 is a plan view of a number of cards forming a unit of the system. Fig. 2 is a sectional view of a set 45 of units detachably secured upon a support.

Fig. 3 is a plan view of several assembled cards showing a modified form of stop. Fig. 4 is a fragmental plan view of a support for the cards and several cards showing a 50 modified form of stop and means for holding the cards down upon the support. Fig. 5 is a fragmental sectional view of a card showing another modified form of stop, and Fig. 6 is a fragmental perspective view of a

card showing still another modified form of 55 stop.

The cards *a* may be of any desired general construction and made of any material, and may be printed in any suitable manner for the purposes intended. The cards have 60 perforations *b* formed in their upper left hand corners, which are formed open at one portion by means of the comparatively narrow slots *c*. A support *d* of suitable sheet material as cardboard, aluminum and 65 the like, provides a support for the cards and a post *e* is secured in the support for mounting the cards thereon. It is preferably in the form of a strip of comparatively thin metal to permit it to be passed through 70 the slot *c* in the card when the card is removed or inserted.

The post *e* preferably constitutes one leg of a staple-like member having its other leg *f* secured in the support at a suitable point 75 to provide a stop for the first or uppermost card of the set of cards *a*, and having the yoke *g* connecting the legs serving as a head for retaining the cards upon their pivotal post *e*. The staple-like post and stop pass 80 through the support and may be clenched or riveted on the rear side or fastened in any other usual and well-known manner.

Stops are provided one for each of the cards. These may be of various constructions and may be placed at various positions upon the cards. They serve to hold consecutive cards from coinciding throughout and thereby permit a uniform space being exposed to view upon each card. 85

In Fig. 1 the stops *h* are formed by slitting each card from the outer side edge upward and rearward forming a V-shaped tab. This tab overlaps the card below and serves 90 as a stop to prevent the engaged card from passing. The height of the slit in this instance determines the space exposed on the card above the stop.

In Fig. 4 the stop *h'* is formed by slitting the card from the lower edge near the outer 100 side edge upward and outward thereby forming a V-shaped top which overlaps the adjacent card to form a stop therefor. In this type of stop the extent to which the cut is made to the outer side edge of the card 105 also determines the space provided between adjacent cards along the upper edge.

The stop shown in Fig. 6 is placed in a

position upon the card similar to that shown in Fig. 1. It is made in the form of a metal clip. The body portion *i* of this stop is folded over the edge of the card and the folded sides pressed tightly to the card. For better securing it, rivets or other devices may be used. The tongue *j* is formed to extend from the body portion and is offset in order that an adjacent card may be held beneath it similarly to the tabs already described.

The stop *h* shown in Fig. 3 resembles an ordinary metal staple passed through the card and clenched in the usual way on the rear side. This construction has the advantage that it may be placed comparatively near the pivotal point of the card. This form of stop does not overlap the adjacent card but on account of being placed near the pivotal point there is little danger that the card held by it will be accidentally lifted high enough during manipulation of the system to bring it over the stop and thus encroach upon the space intended to be left exposed.

The stop shown in Fig. 5 presents another construction that may be placed near the pivot of the cards. This is formed of a folded strip of metal forming a clip *k* which may be secured over the edge of the card by simple pressure or by rivets, as shown, or similar devices.

It is obvious that many other forms of stops may be used than those shown.

The cards are preferably held at their free ends within a circumferential groove *l* which may be formed as shown in Fig. 1 by securing a circular strip of metal *n* upon the support *d* which may also be in the form of a semicircle as shown. The strip is offset to form a space between its inner edge and the support *d* within which the lower outer ends of the cards are confined but with sufficient freedom to permit them to be turned about their pivots.

Fig. 4 shows a different manner of holding the free ends of the cards down upon the supports and a different pivotal connection for the cards. Here a semicircularly bent rod *o* is secured at either end to the support and the tab corners of the cards are placed beneath it with the tabs overlapping it. This rod or wire holds the cards down upon the support, and at the same time, by having part of the card below the rod and another part above or over the rod makes it impossible for an adjacent card to pass the tab and encroach upon the space intended to be exposed. A strip of metal *p* is secured to the support *d* having an upstanding circular flange *q* against which the tab corners of the cards abut thereby confining the cards to a circular path. The cards of this modified form have semicircular open perforations *r* formed in

them which engage the headed posts *s*. With such a construction it is apparent that the cards could leave their pivotal engagement with the post *s* if some such device as the flange *q* were not provided.

The support *d* is preferably formed with an eyelet *t* for securing it to a bent post *u* or other suitable device mounted on a base *v*. The bent post represents any of the well-known loose leaf book devices for receiving the leaves and no further description of it is deemed necessary except that it may be opened at the split joint *w* to remove or insert a unit of the system which includes a support *d* with the cards carried by it. The units may be shifted to either leg of the post in the ordinary manner of loose leaf books.

In the operation of my invention as illustrated in Fig. 1 the cards are mounted on the post *e* by passing it through the open slot *c* in the card until the perforation *b* engages the post; the card is then bulged up in the center temporarily to foreshorten it to permit the lower free end to be slipped in the groove *l*. The card is then permitted to flatten out and is placed in proper position against the stop of the adjacent card.

In this way the system is built upon the support *d* thus forming a unit. The exposed part of the cards may conveniently be used for an index thereby affording a continually exposed index, although it may be used for other purposes if desired. When the body of the card is to be read, written upon or otherwise used the card is held fixed and the adjacent card with all those below it are swung down until the desired card is exposed.

When the card has been thus used as desired, the cards below are then swung back together to their first positions and the unit is ready to be used again. When a card is to be withdrawn or one inserted the division is made in the cards substantially as above described. If a card is to be removed, it is first exposed; it is then withdrawn from the groove and then revolved until the slot *c* is brought in line with the post *e*, in which position it is easily withdrawn from the post. When inserting a card the procedure just described is reversed, the cards being first manipulated to open a space for the card to be inserted.

When removing a card in the form of construction shown in Fig. 4 the card is removed first from the post *s* by bulging the card upward. It is then easily slipped from the rod *o* to clear the tab therefrom by properly swinging it about that corner. The insertion of a card is effected by substantially reversing the steps described.

I have shown only some of the forms of construction embodying my invention, and it is obvious that various changes within the skill of the mechanic may be made therein without departing from the spirit of the

invention, provided the means set forth in the following claims are employed.

Having thus described my invention I claim

- 5 1. In a device of the character described, a number of cards placed one upon the other, a support for the cards, means secured to the support for pivotally engaging the cards, and stops extending one from each card to provide an abutment for the adjacent card when in normal position to provide a continually visible portion on each card and adapting the said adjacent card to be swung about the said means away from its stop from which the adjacent card is moved.

2. In a device of the character described, a number of cards placed one upon the other, a support for the cards, means secured to the support for holding the cards in detachable pivotal engagement and stops extending one from each card to provide an abutment for the adjacent card when in normal position to provide a continually visible portion on each card and adapting the said adjacent card to be swung about the said means away from its stop thereby exposing the card to view containing the stop from which the adjacent card is moved.

3. In a device of the character described, a number of cards placed one upon the other and provided with open slots, a support for the cards, a post extending from the support for engaging the cards through the open slots in pivotal engagement, and stops one on each card affording an abutment for the adjacent card to provide a continually visible portion on each card and adapting the said adjacent card to be swung about the said post away from its stop to thereby expose the card to view containing the stop from which the adjacent card is moved.

4. In a device of the character described, a number of cards placed one upon the other, a support for the cards, means secured to the support for pivotally engaging the cards, stops extending one from each card to provide an abutment for the adjacent card when

in normal position to provide a continually visible portion on each card and adapting the said adjacent card to be swung about the said means away from its stop thereby exposing the card to view containing the stop from which the adjacent card is moved, and 55 a circular guide for engaging free ends of the cards to hold them upon the support.

5. In a device of the character described, a number of cards placed one upon the other, a support for the cards, means secured to 60 the support for pivotally engaging the cards, a circular guide secured to the support in spaced relation therewith for holding the cards within said space, said guide adapted to guide the outer corner of each card in its 65 movement about the pivot, and stops one on each card extending above said space to provide an abutment for the adjacent card when in normal position to provide a continually visible portion on each card and adapting 70 the said adjacent card to be swung about the said means away from its stop thereby exposing the card to view containing the stop from which the adjacent card is moved.

6. In a device of the character described, 75 a number of cards placed one upon the other, a support for the cards having an eyelet formed therein, means secured to the support for pivotally engaging the cards, stops extending one from each card to provide an 80 abutment for the adjacent card when in normal position to provide a continually visible portion on each card and adapting the said adjacent card to be swung about the said means away from its stop thereby 85 exposing the card to view containing the stop from which the adjacent card is moved, and a bent post for engaging said support through the eyelet therein in slidale relation therewith, said post having a joint 90 adapted for opening it to permit the support to be removed or inserted.

This specification, signed and witnessed this 30th day of June, 1913.
